BUTTER VENDING MACHINE

Santiago Castro, Brooklyn, N. Y.

Application January 8, 1941, Serial No. 373,554

12 Claims. (Cl. 194—10)

This invention relates to dispensing or vending machines, and has for its main object the provision of a novel and practical vending machine whereby patters of butter may be obtained by depositing a coin, such as a cent, for each patter.

In eating places, such as cafeterias, an amount of butter is usually served each patron with his portion of bread, which is insufficient for many patrons, and the obtaining of an additional supply of butter is usually an inconvenient or difficult task for both the patron and the attendants. As a result, in some restaurants, a relatively high charge is made for an extra portion of butter, which often displeases the patron and yet brings no profit to the restaurant. It is believed that the present invention will serve a long-felt need on the part both of the restaurant management and the patrons, in that the latter may conveniently and quickly obtain as many additional patters of butter as desired, for a small charge, and the attendants are freed of the inconvenience and trouble of having to serve such extra portions.

The operation of the machine is simple, and as shown embodies a series of identical vertical columns in each of which a cartridge of refrigerated butter is stored. When any cartridge has been used up, it is likewise simple to renew it with a whole new cartridge. The butter remains in the machine at all times in a refrigerated condition. Upon the insertion of a coin into the coin slot, and the subsequent pulling of the lever at the bottom of the column, a single patter of butter is sheared off the bottom of the cartridge and is discharged through the outlet at the bottom, available to the patron. He may set a plate under the discharge opening and thus have the patter discharged onto the plate.

The above and other objects will become apparent in the description below, in which characters of reference refer to similarly-numbered parts in the accompanying drawings which form a part hereof. It is to be understood that the drawings serve the purpose of illustration only, and it is not intended or desired to limit the invention necessarily to the exact details shown on the drawings, excepting insofar as may be within the scope of the invention.

Referring briefly to the drawings, Figure 1 is a front elevational view of the machine, which may be mounted on legs or any other support, not shown.

Figure 2 is a side elevational view of the same.

Figure 3 is a cross-sectional view taken on the line 3—3 of Figure 1.

Figure 4 is a fragmentary plan view of the sliding shearing tongue.

Figure 5 is a cross-sectional view taken on the line 5—5 of Figure 1.

Figure 6 is a cross-sectional view taken on the line 6—6 of Figure 5.

Figure 7 is a cross-sectional view taken on the line 7—7 of Figure 5.

Figure 8 is a cross-sectional view taken on the line 8—8 of Figure 5.

Figure 9 is a wiring diagram.

Referring in detail to the drawings, the numeral 10 indicates the overall housing containing the device, this housing having an extension housing 11 forward thereof. A tray 12 is mounted under the extension 11, and the latter is divided into a plurality of horizontally spaced vertical compartments 13. A door 14 is hingedly mounted above the extension housing 11 and is adapted to be swung upward to give access to the compartments 13; key-locking means are provided to lock the door in closed position.

In the interior 15 of the main housing 10, any suitable refrigerating unit, shown at 33, may be provided. One or more outlets for cold air into the housing 14 are shown at 34. The compartments 13 are open at the rear so that free communication, or circulation of air, is provided between the compartments 15 and 13; thus, the contents of the compartments 13 are maintained at a low or refrigerated temperature.

A coin slot 16 is provided on one side of the housing 10, and a coin chute 17 extends downward therefrom. A door 18, hinged at 19 to the bottom of the chute 17, provides normal closing means for the bottom of the chute. This door is in the form of a simple lever and has an arm 20 extending from the fulcrum thereof. A pin 21 on the arm 20 is slidably engaged in the vertical slot 22 of a vertical rod 23.

A contact closing flap 24 is hingedly mounted at 25 to the rear wall of the chute 17, above an opening 26 in said wall. A fine coiled spring surrounds the hinge 25 and normally urges the flap 24 in a clockwise direction; a limit stop 27 retains the flap 24 in the normal raised position shown. A bracket 28, of insulating material, is secured to the outside of the rear wall of the chute 17 and is provided with a pair of spaced contacts 29 which project through the bracket 28 into the opening 26. A metallic plate 30 is secured to the underside of the flap 24, separated therefrom by insulation. When a coin is dropped into the slot 16 and falls down the chute, the weight thereof, resting against the flap 24, forces

the latter against the contacts 29, thus closing the circuit therethrough. A coin box or receptacle 31 is positioned under the chute 17, and is normally closed by a key-locked door 32 which gives access thereto from without.

Although a plurality of vertical compartments 13 are shown, the vending and dispensing mechanism is illustrated as applied to but one of the compartments, and it may of course be applied to all of the compartments by mere duplication. All but the lower portion of the front of the extension housing 11 is covered by a glass panel 35 set in a frame 36. In the lower portion 31 of this front wall, a plurality of knobs or handles 38, each fixed to a cross-bar 39, are provided, one knob for each compartment 13. The compartments are normally closed at the bottom by a horizontal plate 40, which will be described further below. A column of butter 41, square in cross-section, is mounted upright in each compartment 13 and rests on the plate 40 in each compartment. On top of each column of butter, a weight 43 is placed, to urge the column downward at all times. For sanitary reasons, the column of butter is wrapped in tissue or wax paper, or cardboard, 43, which is perforated peripherally along spaced horizontal planes, the vertical distance between the perforations 44 defining the thickness or height of each patty of butter. Each compartment 13 has rigidly mounted therein a vertical tube 45, square in cross-section, whose front side has the opening 46 therein so as to give visibility to the column through the front glass 35; and it is within this tube that the column of butter is mounted. The opposed side walls 47 of the tube 45 are provided with vertical slots 48, in which opposed lugs 49 on the weight 43 register.

The cross-bar 39 has a pair of spaced parallel bars 50 rigid with the ends thereof and extending slidably rearward through vertical slots, not shown, in the panel 31 and the dividing wall 51 between the housings 10 and 11. The inner portions of the bars 50 have racks 52 on their upper edges. Supported in ears 53 is a horizontal shaft 54 having spaced pinions 55 rigid thereto and in mesh with the racks 52. A horizontal slot or opening 56 passes through the wall 51 just below the lowermost end of the rigid tube 45, and a vertically slideable door 57 is mounted rearward of this opening against the wall 51; the door 57 is slideable in vertical guides 58 and has integral therewith, on each side, a vertical rack 59. The racks 59 are also in mesh with the pinions 55. It is thus obvious that pulling out the knob 38 draws out the bars 50, rotates the pinions 55 in a clockwise direction and causes the latter to raise the door 57.

The plate 40, above-mentioned, passes slidably through an opening through the wall 51, and it has depending from each side edge thereof a rigid flange 60 provided with rack teeth along its lower edge. These flanges or racks 60 also pass slidably through openings in the wall 51, together with the plate 40. Pinions 62, rigid on the shaft 63 supported in the ears 64 against the wall 51, are in mesh with the racks 60. The pinions 62 are also in mesh with the racks 59. It is thus apparent that as the door-opening racks 59 are raised, as above described, the plate 40 is simultaneously drawn rearward.

A knife blade 65 is secured at its widened rear end 66 between the racks 50, and has an upright cross member 67 rising above the racks 50. A spring 68, anchored to the rear wall of the hous-

ing 10 and secured to the member 67, normally urges the knife 65 rearward. A series of loops of a heating wire 68 are mounted within the blade 65, and the terminals of this wire are shown at 69.

Mounted beneath the blade 65 is a solenoid 70 having its armature 71 secured in the arms 72 which are rigid on a pivotally mounted horizontal shaft 73. One arm 72 has an extension 74 in which a spring 75, anchored to the floor of the housing, is secured; this spring normally urges the armature upward, away from the solenoid. Each rack 50 has an indent 76 in its lower edge, in which the noses 77 (one on each arm 72) normally register so as to prevent withdrawal, forward, of the bars 50.

As shown in the wiring diagram, when a coin falls to the bottom of the chute 17 and closes the circuit through the contacts 29, current flows simultaneously through the heating wire 68 of the knife 65, heating the knife, and through the solenoid 70, drawing down the armature 71 and the arms 72 and releasing the dogs 77 from the indents 76; whence the knob 38 may be drawn forward. The knife 65 and its heating element 68 would of course be so constructed that the knife would become quite warm, or hot, within a very small space of time after the said contact is closed. The elevation of the blade edge above the plate 40 is, of course, equal to the vertical distance between the perforations 44 in the wrapper 43 around the column of butter 41. As soon as the knob 38 moves forward, then, the door 57 begins to rise and the plate 40 begins to recede. By the time the cutting or forward edge of the blade 65 reaches the opening 56 the door will have risen above this opening so that the blade may pass through. The heated blade will readily cut through the butter and its perforated wrapper, and when it has passed forward to the limit of its movement, as set by the upright 67 which serves as a limit stop, it will have sheared off the lowermost patty of butter; and as the plate 40 will by that time have receded from the tube 45, the sheared patty will fall into the tray 12. Upon release of the knob it and its associated parts will, because of the springs 68 and 75, resume their former or inactive positions; and the column of butter will fall to rest again on the plate 40.

The rod 23 is pivoted at its lower end to the top of one rack 59. A spring 78 normally holds the door 18 closed, as shown. It is apparent that, as the racks 59 rise in accordance with the operation described above, the bar 23 will also rise, and when the racks 59 have reached the peak of their upward movement the bar 23 will have risen sufficiently to cause the lower end of the slot 22 therein to trip the door 18 and permit the coin in the chute to fall into the coin box, thus opening the switch 29-30. Restoring of the parts above-mentioned to normal position upon release of the knob, will also, obviously, restore the door 18 to its normal closed position, simultaneously.

The knife blade 65 may be used either with the heating element described or without it, as is obvious. The closing of the door 57 serves to insulate the still warm blade 65 from the refrigerated column of butter. If the heating element of the knife is omitted, this door and its operating mechanism could be dispensed with. The column of butter, furthermore, could be cut into separate patties prior to insertion into the compartment 13, with each patty separately

wrapped in tissue paper, but this would be more expensive. It is believed that the machine as illustrated and described is most efficient and economical in operation, and will completely fulfill the objects set forth.

Obviously, modifications in form and structure may be made without departing from the spirit and scope of the invention.

I claim:

1. A machine comprising a housing having a vertical compartment therein adapted to have a column of butter slidably mounted therein, a member slidably mounted in the front and rear wall of the compartment and having a handle secured thereon forward of said front wall, a plate slidably mounted in said rear wall and normally protruding into said housing, said column resting by gravity on said plate, a knife secured to said member, said rear wall having a horizontal opening therethrough on the level of said knife, and means connecting said member and said plate for moving said plate rearward simultaneously as said member is pulled forward, the pulling forward of said member causing said knife to pass through said opening and shear off the lower end of said column, said means comprising a rack on said member and a rack on said plate, an intermediate vertical rack, and pinions connecting said first two racks with said intermediate rack.

2. A machine comprising a housing having a vertical compartment therein adapted to have a column of butter slidably mounted therein, a member slidably mounted in the front and rear walls of the compartment, a plate slidably mounted in said rear wall, said column resting by gravity on said plate, a horizontal knife secured to said member and normally protruding into said housing, said rear wall having a horizontal opening therethrough on the level of said knife, a door vertically slidably mounted on said rear wall against said opening, and means connecting said member, said plate and said door for moving said plate rearward and sliding said door clear of said opening simultaneously as said member is pulled forward, the pulling of said member forward causing said knife to pass through said opening and shear off the lower end of said column.

3. A machine comprising a housing having a vertical compartment therein adapted to have a column of butter slidably mounted therein, a member slidably mounted in the front and rear walls of the compartment, a plate slidably mounted in said rear wall, said column resting by gravity on said plate, a horizontal knife secured to said member and normally protruding into said housing, said rear wall having a horizontal opening therethrough on the level of said knife, a door vertically slidably mounted on said rear wall against said opening, and means connecting said member, said plate and said door for moving said plate rearward and sliding said door clear of said opening simultaneously as said member is pulled forward, the pulling of said member forward causing said knife to pass through said opening and shear off the lower end of said column, and means for restoring said member, said plate, and said first-named means to normal position upon release of said member.

4. A machine comprising a housing having a vertical compartment therein adapted to have a column of butter slidably mounted therein, a member slidably mounted in the front and rear walls of the compartment and having a handle

secured thereon forward of said front wall, a plate slidably mounted in said rear wall and normally protruding into said housing, said column resting by gravity on said plate, a knife secured to said member, said rear wall having a horizontal opening therethrough on the level of said knife, and means connecting said member and said plate for moving said plate rearward simultaneously as said member is pulled forward, the pulling forward of said member causing said knife to pass through said opening and shear off the lower end of said column, said knife having electrical heating means, releasable locking means normally locking said first-named means against said pulling out of said member, and coin-operated electrical means for simultaneously releasing said locking means and energizing said heating means.

5. A machine comprising a housing having a vertical compartment therein adapted to have a column of butter slidably mounted therein, a member slidably mounted in the front and rear walls of the compartment and having a handle secured thereon forward of said front wall, a plate slidably mounted in said rear wall and normally protruding into said housing, said column resting by gravity on said plate, a knife secured to said member, said rear wall having a horizontal opening therethrough on the level of said knife, and means connecting said member and said plate for moving said plate rearward simultaneously as said member is pulled forward, the pulling forward of said member causing said knife to pass through said opening and shear off the lower end of said column, said knife having an electrical heating element therein, a source of electricity, a coin operated switch in circuit with said element and said source, said switch having means for closing said circuit upon inserting a coin into the machine, releasable locking means normally locking said first-named means against said pulling out, electrical means for releasing said locking means, said switch and said electrical means being in parallel circuit with said source.

6. A machine comprising a housing having a vertical compartment therein adapted to have a column of butter slidably mounted therein, a member slidably mounted in the front and rear walls of the compartment and having a handle secured thereon forward of said front wall, a plate slidably mounted in said rear wall and normally protruding into said housing, said column resting by gravity on said plate, a knife secured to said member, said rear wall having a horizontal opening therethrough on the level of said knife, and means connecting said member and said plate for moving said plate rearward simultaneously as said member is pulled forward, the pulling forward of said member causing said knife to pass through said opening and shear off the lower end of said column, said knife having an electrical heating element therein, a source of electricity, a coin operated switch in circuit with said element and said source, said switch having means for closing said circuit upon inserting a coin into the machine, releasable locking means normally locking said first-named means against said pulling out, electrical means for releasing said locking means, said switch and said electrical means being in parallel circuit with said source, and means for simultaneously releasing the coin and opening said switch when said member has been pulled forward to its maximum.

7. A machine comprising a housing having a vertical compartment therein adapted to have a column of butter slidably mounted therein, a member slidably mounted in the front and rear walls of the compartment and having a handle secured thereon, a plate slidably mounted in said rear wall and normally protruding into said housing, said column resting by gravity on said plate, a knife secured to said member and normally positioned rearward of said compartment, said rear wall having a horizontal opening therethrough on the level of said knife, means connecting said member and said plate for moving said plate rearward simultaneously as said member is pulled forward, the pulling forward of said member causing said knife to pass through said opening and shear off the lower end of said column, said knife having electrical heating means, and coin-operated electrical means for energizing said heating means prior to said pulling forward of said member.

8. In a machine having a compartment adapted to contain a column of butter or the like and having a normally cool slide knife positioned adjacent said column adapted to be slid forward to shear said column, means for supplying heat to said knife prior to said forward sliding of said knife and means for cutting off said heat supply after completion of said forward sliding.

9. In a machine having a compartment adapted to contain a column of butter or the like and having a slide knife positioned adjacent said column adapted to be slid to shear said column, said knife having an electrical heating element associated therewith, a switch and a

source of electricity in circuit with said element, means for operating said switch, said switch being adapted to be closed by said means prior to said forward sliding of said knife, and means for actuating said switch-operating means to open the switch upon completion of said forward sliding of said knife.

10. In a machine having a compartment adapted to contain a column of butter or the like and having a slide knife positioned adjacent said column adapted to be slid forward to shear said column, said knife having an electrical heating element associated therewith, a switch and a source of electricity in circuit with said element, and means for automatically opening said switch upon completion of said forward sliding of said knife.

11. A slot machine having a coin operated switch and a slide adapted to be moved longitudinally a limited distance, said slide having a heating element thereon, a source of electricity in circuit with said switch and said element, a coin trap associated with said switch having means for holding a deposited coin against said switch to close said switch and adapted to be tripped to release said coin from said switch to open said switch, and means for automatically tripping said trap and thereby opening said switch after said slide has been moved through said limited distance.

12. A machine in accordance with claim 11 wherein additional means is provided for restoring said slide and said trap to their original positions upon release of said slide.

SANTIAGO CASTRO.
